Nathaniel P. Richardson, of Portland, Maine.
Letters Patent No. 1048, dated Sept. 7-1858.

The Schedule referred to in these Letters Patent and making part of the same.

To all whom it may concern:

Be it known that I, Nathl. P. Richardson, of the City of Portland, County of Cumberland and State of Maine, have invented or produced a new and original design for the Top, Bottom, Door, Legs and cover to be used in making a "Sheet Iron Air Tight Stove" so called, and I do hereby declare, that the following is a full and exact description of the same, reference being had to the accompanying drawings and to the letters of reference theron,

Of the said drawings, Figure 1. denotes a perspective view of the Top and Cover,

Figure 2. is a transverse section of the same, taken through the line A. A.

Figure 3. is a cross section of the same taken through the line B. B.
Figure 4. denotes the design of the Bottom as also the Door C & Leg D.
Figure 5. is a cross section of the Bottom taken through the line E. E.
Figure 6. is a cross section of the Door C taken through the line H. H.
Figure 7. is a longitudinal section of the Leg D, taken through the line I. I.

What I claim as my invention is the ornamental design for a Top, Bottom, Cover, Door, and Legs for a Sheet Iron Air Tight Stove substantially as exhibited in the accompanying drawings and as described above.

In testimony whereof I have hereunto set my hand and seal
this twenty fourth day of July A. D. 1858.

Witnesses.

Joshua Richardson.
